UNITED STATES PATENT OFFICE.

JOHN BIGLANDS PEARSON, OF DUBLIN, IRELAND.

STANDARD FOR WIRE FENCES OR SIMILAR PURPOSES.

1,122,997.

Specification of Letters Patent. Patented Dec. 29, 1914.

Application filed April 24, 1914. Serial No. 834,258.

To all whom it may concern:

Be it known that I, JOHN BIGLANDS PEARSON, a British subject, residing at Dublin, Ireland, have invented certain new and useful Improvements in Standards for 5 Wire Fences or Similar Purposes, of which the following is a specification.

This invention relates to improvements in standards or posts for strained wire and other fences, and particularly to standards 10 made of sheet iron or other metal wherein the wires are made to pass through the center of the standard or post. The standard is suitable for use with barbed wire, interlaced or woven wire, or electrically welded 15 wire.

The invention consists in making each standard in three parts, one part being prepared to take the wires and provided with 20 a base which is placed in earth or concrete as desired, one part being formed to slide over the first part and lock the wires in position and one part being formed as a base for the locking piece.

25 The invention will be fully described with reference to the accompanying drawings forming part of the specification.

Figure 1 is a front elevation of the standard. Fig. 2 is a side elevation of same. 30 Fig. 3 is an enlarged section on line $\alpha-\alpha$ Fig. 1. Fig. 4 is an enlarged section on line $y-y$ Fig. 1. Fig. 5 is an enlarged perspective view of the parts A and B.

The standard is formed in three parts, 35 the member A which carries the wires, the member B which slides over the member A and locks the wires in position and the member C which forms a half base for the locking member B.

40 The member A which carries the wires is made approximately U-shape in cross section and the vertical edges a of this member are bent as shown in the drawings to form a slide or guide for the edges b of the locking member B. Holes or slots a' are formed in the edges a of the member A to receive the wires D. The member B is also 45 made approximately U-shape in cross section and the edges b thereof are bent to pass around the edges a of the member A which 50 form a guide for the edges b .

The lower end of the member A is provided with an approximately U-shaped base A' to which is attached a U-shaped 55 base C for the member B so that the latter can be placed in position after the standard

has been erected and can be removed at any time as described by drawing it up from the standard.

The slots or holes a' to receive the wires 60 D can be placed at any desired position to suit the different spaces of the wires and the whole standard is held together by a cap E at the top which is secured by a hook bolt e' and nut e the hook bolt clipping 65 round the top fence wire as shown in Fig. 2.

The standards may be galvanized or painted and may be fixed in earth, concrete, or other suitable material. When erecting, the member A and the half base C are fixed 70 in the earth or concrete, the wires D are then placed in the slots a' and the locking member B slipped over the member A from the top. The cap E is then placed in position, the hook bolt e' inserted under the top 75 wire and the nut e tightened until the whole standard is firmly held together. When it is required to remove the locking member B for any purpose it is only necessary to unscrew the nut e remove the hook bolt e' 80 and cap E and draw up the member B.

What I claim as my invention and desire to protect by Letters Patent is:—

1. A standard for fence wires comprising, in combination, a member of substantially 85 U-section, having its longitudinal edges turned laterally outward, and bent to form continuous guides of angle section, said edges being provided with slots for the passage of the wires therethrough; a complementary member of substantially U-section, having its longitudinal edges turned laterally outward and bent around said guides, to retain the wires in said slots; and a cap 90 fitted over the upper ends of said members, 95 to hold the same together.

2. A standard for fence wires comprising, in combination, a member of substantially U-section, provided at its lower end with a similar shaped base, said member and base 100 having their longitudinal edges turned laterally outward and bent to form continuous guides of angle section, the bent edges of said member being formed with wire-receiving slots; a base complementary 105 to the first-named base and adapted to be driven therewith into the ground, the second-named base having its longitudinal edges bent around the guides on the first-named base; a member of substantially U- 110 section complementary to the first-named member and detachably fitted at its lower

end upon the top of the second-named base, said member having its longitudinal edges turned laterally outward and bent around the guides on said first-named member, to retain the wires in said slots; and a fastening device fitted over the tops of said members to hold the same together.

Copies of this patent may be obtained for five cents each, by addressing the "Commissioner of Patents, Washington, D. C."

In testimony whereof I have hereunto set my hand in presence of two subscribing witnesses.

JOHN BIGLANDS PEARSON.
